*Primary Examiner—Lucy J. Lieberman**Attorney, Agent, or Firm—Stephan P. Williams***[57] CLAIM**

The ornamental design for a combined roll-on dispenser and cap, as shown.

DESCRIPTION

FIG. 1 is a perspective view as seen from the top, front and left side of the combined roll-on dispenser and cap of my new design;

FIG. 2 is a top plan view thereof;

FIG. 3 is a front elevational view thereof, the rear elevation being a mirror image thereof;

FIG. 4 is a bottom plan view thereof; and,

FIG. 5 is a right side elevational view thereof, the left side elevation being a mirror image thereof.
